UNITED STATES PATENT OFFICE

EDWARD J. SEXTON, OF INDIANAPOLIS, INDIANA

RAILROAD CROSSING

Application filed July 17, 1929. Serial No. 378,972.

This invention relates to railroad crossings and the prime feature of the invention is the provision of means for providing a continuous rail surface in either direction for the 5 passage of a train.

A further feature of the invention is the provision of means for simultaneously closing the parts of one trackway for the passage of a train, while the parts of the other track- 10 way are moved to open position.

A further feature of the invention is the provision of means for locking the parts of the device in adjusted positions.

A further feature of the invention is the 15 provision of means for retaining the movable parts of the device against tilting action.

A further feature of the invention is the provision of means for reinforcing the connecting parts of the device.

20 Other objects and advantages will be hereinafter more fully set forth and pointed out in the accompanying specification.

In the accompanying drawings which are made a part of this application,

25 Figure 1 is a top plan view of the device set to afford a continuous rail surface over one trackway.

Figure 2 is a similar view showing the parts set to form a continuous rail surface over the 30 other trackway.

Figure 3 is an edge elevation of the trackways and the operating means therefor.

Figure 4 is a similar view of the locking mechanism.

35 Figure 5 is an end elevation of one of the shifting rail sections.

Figure 6 is a perspective view thereof, and,

Figure 7 is a detail sectional view as seen along lines 7—7, Fig. 2.

40 Referring to the drawings in which similar reference numerals designate corresponding parts throughout the several views, the numeral 1 indicates the rails forming one of the trackways, and 2 indicates the rails forming the other trackway.

The trackway 1 is substantially at right angles to the trackway 2 and the connecting rails 3 between the rails of the trackways 1 and 2, are right angular shaped and prefer- 45 ably in one piece, so that the wheels of a train

will pass thereover without causing undue clicking or pounding noise. Interposed between the connecting rails 3, are subrails 4 and 5, which form continuations of the rails of the trackways 1 and 2 respectively. The 55 connecting rails 3 and the sub-rails 4 and 5 are secured in any suitable manner, to a base 6, preferably of metal and the rails of the trackways 1 and 2 are connected with the connecting rails 3 through the medium of fish plates 7 and 8, the plates 7 being preferably triangular shaped, while the plates 8 are substantially channel shaped, the latter plates forming braces for the subrails 4 and 5. 60

In order to permit the wheels of a train to 65 pass over one of the trackways without encountering the rails of the other trackway, the sub-rails 4 and 5 have movable sections 9 and 10 respectively, at their ends, which operate in pairs and are arranged so that when one set of the sections are adjusted to form continuous rails for one trackway, the other set will be moved out of alignment with the rails of the other trackway.

To accomplish this result, a rocking shackle member 11 is pivoted to the base 6, centrally between the sub-rails 4 and 5, two of the movable sections 9 and two of the movable sections 10 being connected directly to the arms of the shackle member 11 by means of pitmen 12 and 13, respectively, while the other two of the movable sections 9 and 10 are connected to levers 14 and 15 respectively, by means of links 16 and 17, said levers being in turn connected to the arms of the shackle member 11 through the medium of pitmen 18 and 19, respectively, all of said pitmen being adjustable lengthwise. 75 80 85

By shackling the several movable sections 9 and 10 in the manner shown, four of the movable members will be simultaneously moved into alignment with two of the subrails, while the other four members will be moved out of alignment with two of the subrails, when the shackle member 11 is rocked back and forth on its pivot, the pitmen 18 and 19 being in crossed relation with each other for causing the movable members associated therewith to move in their prescribed 90 95 100

directions incident to the operation of the shackle member.

The movable members 9 and 10 each have depending blocks 20 thereon, which slide in 5 guide slots 21 in the base 6, said movable members being further guided and braced by forming ledges 22 on the base portions of said members which extend beneath and enter grooves 22A in the cooperating rail members 10 and prevent lateral swaying motion thereof while a train is passing thereover.

The shackle member is operated and controlled in any suitable manner and from any suitable position, the controlling mechanism 15 herein shown being located adjacent the crossing, although it may be located in a tower (not shown) or at any suitable distance from the crossing. The operating mechanism comprises a lever 23, pivoted to a support 24, one end of the lever 23 having a rod 25 attached thereto, the opposite end of said rod being attached to one arm of a bell crank lever 26, pivoted to the base 6 or other suitable point.

25 Attached to the opposite arm of the bell crank lever 26 is a rod 27, the opposite end of said latter rod being attached to one of the arms of the shackle member 11, so that when the lever 23 is swung back and forth on its 30 pivot, the shackle member 11 will be swung back and forth in the arc of a circle and the various sets of movable members moved into or out of operative position.

In order to lock the various movable members 9 and 10 in their respective adjusted positions, a locking rod 28 is provided, one end of which is attached to an operating lever 29, while the opposite end thereof passes through openings in a sliding plate 30, a 35 guide member 31 being provided for properly guiding the plate 30. The plate 30 is moved endwise incident to the longitudinal movement of the rod 27, to which the sliding plate 30 is attached. The holes (not 40 shown) in the plate 30 are preferably two in number, one of which is in position to receive the end of the locking rod 28, when one set of the movable members is in operative position and with the other opening when the other 45 set of movable members is shifted to operative position.

In operation, supposing that a train is to pass over the crossing on the trackway 1, the parts of the device are set in the positions 50 shown in Fig. 1, the movable members 9 being in alignment with the rails forming the trackway 1, while the movable members 10 are out of alignment with the rails forming the trackway 2, thus forming a continuous bearing surface for the wheels of the train in one direction. In the event the train is to pass over the trackway 2, the lever 29 is operated to release the plate 30, after which the lever 23 is operated to rotate the shackle member 55 11, which will result in positioning the mov-

able members 10 in alignment with the rails forming the trackway 2 and move the members 9 out of alignment with the rails forming the trackway 1 as shown in Fig. 2. The lever 29 is again operated to engage the locking rod 28 with an opening in the plate 30 and again lock the movable members in their adjusted positions, the locking of the plate 30 preventing the adjustable members moving out of position until the entire train has 75 passed thereover.

While I have illustrated in a general way, certain instrumentalities which may be employed in carrying my invention into effect, it is evident that many modifications may be made in the various details, without departing from the scope of the appended claims, it being understood that my invention is not restricted to the particular examples herein described.

What I claim is:

1. In a crossing structure, a base member, track forming rails on said base member and in crossing relation, connecting rails for said track forming rails, sub-rails between said connecting rails and spaced therefrom, the ends of said sub-rails and said connecting rails having undercut grooves therein, movable members adapted to be moved into or out of position between the ends of the sub-rails and said connecting rails, ledges formed on said movable members adapted to enter said grooves when the movable members are positioned between the ends of said sub-rails and said connecting members for holding 100 said movable members rigid while a train is passing thereover, blocks depending from said movable members forming guides therefor, said base member having slots therein for the reception of said blocks, and means 105 for disposing said movable members into or out of position between said sub-rails and connecting rails.

2. In a crossing structure, a base member, track forming rails on said base, connecting rails for said track forming rails, sub-rails between said connecting rails and spaced therefrom, movable members adapted to be moved into or out of position between said connecting and sub-rails, a shackle member pivoted 110 to said base member, pitmen connecting said shackle member with said movable members, a rod for rocking shackle member, a lever for operating said rod, a perforated plate, means for connecting said plate with said shackle member whereby the plate will slide longitudinally when the shackle member is rocked, a locking rod adapted to engage the perforations in said plate for locking the shackle in its rocked position, and a lever for operating 115 said locking rod.

In testimony whereof, I have hereunto set my hand on this the 10th day of July, 1929,
A. D.

EDWARD J. SEXTON. 120
